UNITED STATES PATENT OFFICE.

FRANCIS M. UNDERHILL, OF BROOKLYN, ASSIGNOR TO WHITALL, TATUM & CO., OF NEW YORK, N. Y.

DESIGN FOR A BOTTLE.

SPECIFICATION forming part of Design No. 18,997, dated April 2, 1889.

Application filed February 6, 1889. Serial No. 298,905. Term of patent 14 years.

To all whom it may concern:

Be it known that I, FRANCIS M. UNDERHILL, a citizen of the United States, residing at Brooklyn, in the county of Kings and State of New York, have invented and produced a new and original Design for a Bottle, of which the following is a specification, reference being had to the accompanying drawings, forming part hereof, in which—
10 Figure 1 is a face view of my newly-designed bottle. Fig. 2 is a side view thereof, and Fig. 3 is a horizontal section of the same on the line *c c*, Fig. 1.
The leading feature of my design consists in
15 a bottle having substantially flat sides and rounded corners and a recess extending along one side and around the adjoining corners, said recess being straight at the back and rounded at the corners.

In the accompanying drawings, A represents my newly-designed bottle, the sides *a* of which are substantially flat and the corners *b* are rounded.

d is a recess extending along one side, *a*, and around the two adjoining corners *b*. This recess is flat at the back and rounded at the corners, as shown.

I claim—

The design for a bottle, the same having substantially flat sides *a* and rounded corners *b*, and a recess, *d*, extending along one side, *a*, and around the two adjoining corners *b*, said recess being straight at the back and rounded at the corners, substantially as shown.

FRANCIS M. UNDERHILL.
